UNITED STATES PATENT OFFICE.

MICHAEL J. BURNS, OF LOWELL, MASSACHUSETTS, ASSIGNOR TO THE GAMEWELL FIRE-ALARM AND TELEGRAPH COMPANY, OF NEW YORK, N. Y.

POLICE-SIGNAL.

SPECIFICATION forming part of Letters Patent No. 516,641, dated March 20, 1894.

Application filed October 26, 1893. Serial No. 489,184. (No model.)

To all whom it may concern:

Be it known that I, MICHAEL J. BURNS, a citizen of the United States, residing at Lowell, in the county of Middlesex, State of Massachusetts, have invented a certain new and useful Improvement in Police-Signals, of which the following is a specification.

My invention relates to a system of police signals, in which means are provided for sending to the central station signals of different kinds from any one of a series of boxes located on the circuits radiating from the central station. With a system of this kind it has heretofore been common to provide for sending signals of two different classes, one class being known as "duty calls" and the other as "emergency calls." It is so arranged that each box can be utilized to send in a number of calls of each class. The signals in the class of duty calls are those sent by the different officers using any box when they simply report their presence. Under the class of emergency calls, however, there are usually three or more, which may be sent in, and they all indicate some special emergency. For instance, it is possible to send signals indicating an ambulance call, a telephone call, and either a slow or fast wagon call. To send any desired call from a box, excepting in some cases the fast wagon call, it is only necessary for the officer to open the box, set the pointer at the desired signal, and then pull a lever to start the mechanism, but the fast wagon call in some cases is made by inserting a key from outside the box with door closed. At the central station means are provided for receiving and distinguishing the different classes of calls.

My invention relates both to the transmitting boxes and to the receiving apparatus. Under the present arrangements, whenever an emergency call is received at the central station which requires a wagon to be sent out the proceedings are usually about as follows: The apparatus for sending wagon calls from the central station or police office to the police stable consists of a gong and striker and a step-by-step box number indicator placed in the police stable and arranged in an open local circuit and a step-by-step transmitter, also included in said local circuit and placed

in said police office or central station, said transmitter requiring that the person in charge thereof shall first learn the number of the signal box from which the call was sent, 55 turn an index-finger to the same number on the dial of a transmitter and then press a lever by hand to close the circuit. But usually no particular person has exclusive charge of the register and the call from the 60 central station to the stable is sent by the officer who happens to be nearest the transmitter, so that there is sometimes a considerable delay after a wagon call is received before the wagon driver is notified. This time 65 is spent by the officer in stopping the alarm or bell, learning the nature of the call, and getting the number of the signal box which sent it in. When the wagon driver receives the signal, he hitches his horse into the wagon 70 and drives to the door of the station to receive the officers, whose business it is to go to the signaling sub-station. With the present system, it frequently happens that more time is consumed in getting the wagon to the police 75 station door after a wagon call is received at the central station than is occupied in going from the central station to the sub-station from which the call was sent, a matter of very great importance in case of a riot or attempt to rescue a prisoner or assault upon an officer.

The object of my invention is to avoid the necessity for such delay by means of devices by which such calls as demand the sending 85 of the wagon shall be automatically indicated at the stable as well as at the central station, and that there shall also be kept at the stable an automatic record of the call and hour of its reception, and the same signal also will 90 open the stable door and ring an alarm. By this means the police signaling system will be reduced to the same degree of perfection as has been already attained in the fire alarm system wherein practically the first break in 95 the circuit is used to release the horses in order that they may be ready to start from the engine house almost as soon as the box number has been indicated.

My invention is illustrated in the accompanying sheet of drawings in which is illustrated diagrammatically the apparatus and

circuits for a local station A, the central station B, and the stable C respectively. The local station A is one of a number of similar stations A', A², A³, &c., located upon a circuit extending to the central station. The circuit contains two distinct metallic lines *a*, *b*, and the apparatus at the local station is for the most part of well known construction and particularly used at the present time for sending different classes of signals, and known as a multiple signal box. I have selected for illustration the form of multiple signal box usually employed by the Gamewell Fire Alarm and Telegraph Company, the principal features of which are well known so that it will not be difficult to understand the additions which I have made to a signal box of this kind. It will also be possible for any one skilled in the art to adapt my invention to other kinds of boxes.

The two classes of signals generally employed are known as duty calls and emergency calls. The former being those sent by an officer when reporting and the other being employed when it is necessary to telephone to the central station or to have an ambulance or patrol wagon summoned. In the Gamewell signal box, as is well known, it is necessary for the officer in sending the call to turn a pointer to the desired call and then pull the releasing hook. To give the fast wagon call, it is only necessary to insert a special key known as a "citizen's key" from the outside of the box and turn it, it being unnecessary to open the door of the box as in other signals. The object of this is to make it possible for a citizen having a citizen's key to send the fast wagon call by simply turning the key in the lock.

Referring to the drawing of the local station apparatus, D is the break wheel for giving the number of the box, and E is the contact spring bearing upon the periphery of the wheel.

F is the notched wheel connected with the pointer on the outside of the inclosing case, which is turned by the officer in sending the signal. This wheel I will refer to as the pointer wheel, the purpose of this wheel, as is well known, being to produce the breaks in the circuit which indicate the character of the call, while the break wheel D gives the box number. The turning of the pointer wheel to any desired degree determines the character of the call.

H is a lever having at one end a friction wheel bearing on the periphery of the pointer wheel so as to be oscillated by the notches thereon. Upon the other end of lever H is a contact spring *p* bearing against the anvil K. The contact spring and anvil are brought into the main line by suitable circuits, and the contact broken between them by the oscillations of lever H occasioned by the notches in the periphery of the pointer wheel, the number of the oscillations being determined by the number of notches which act upon the

lever. The break wheel D is operated in the usual manner by a clock train, and it in turn moves the pointer wheel by the engagement 70 of a toothed sector *d* with corresponding teeth *c* on the periphery of the latter wheel. If, therefore, the pointer wheel is turned to the left in the direction of the small arrow by the officer in setting the pointer, and break 75 wheel D is then released, the rotation of the latter will rotate the former to a degree determined by the position at which it has been set, and thereby produce a certain number of breaks in the main line between anvil K 80 and the contact spring *p*, and after these breaks have occurred, the continued rotation of D will add the box number to the signal. This in general is the method of operation of the box, but there are a number of changes 85 in the circuits, some of which are provided in carrying out the improvements which I have made to the box, and others of which pertain to the box as it has been heretofore used. 90

For sending the fast wagon call the pointer wheel is not used as the springs controlled by cams C', C² and those controlled by lever P are arranged to send this signal. It consists of a long break followed by the box number. 95 This call is sent while the door is shut by inserting a key in the lock, which when turned releases the clock train and as the line is then under the control of the contact springs the signal consists as aforesaid of a long dash followed by the box number to be sent. I have found it necessary to add additional contact springs which are acted upon by the multiple lever P by means of which the signal will be sent mainly over line *a*, but will be accompanied by a momentary break in line *b* including the loop for that part of the circuit which goes to the stable. Previously all of the duty calls were sent on the line *a* only, the line *b* being reserved principally for telephonic purposes. For emergency calls, however, a momentary impulse has been sent over part of the line *b* to operate the bell, by the ringing of which emergency calls are distinguished, and to carry out my invention I 105 have provided that a similar momentary use shall be made of all the line *b* whenever a wagon call is to be sent. Thus as the line *b* includes also a relay at the stable, this relay provides the means by which the wagon calls 110 only are received at the stable. 115

Taking up now the details of the invention, the normal condition of the circuits and apparatus will be described, and also the several conditions under which it is operated. 125

At the central station X is the main relay, Z is a battery upon line *a*, and Y is a smaller battery upon line *b*. The local register magnet V (and at times the stable magnet U' as well) is controlled by the main relay X, and the circuit of bell magnet W is also controlled by the main relay magnet. The stable C contains a relay magnet U which is included in the line *b* by a loop *b'*. This magnet U con-

- trools the local door magnet T, and the intermediate local relay magnet S which in turn controls the circuit of the local register magnet U'.
- 5 At the local station A there is a normal short-circuit around the whole apparatus maintained closed by the spring R resting upon the toothed sector d, which is at once broken by the movement of the mechanism.
- 10 This short-circuit is from the terminal a' to spring E, to wheel D, to sector d, to spring R, point 4, to point 5, to terminal a². As this short-circuit is immediately interrupted it will be hereinafter disregarded in the description of the apparatus. The normal circuit (the short-circuit being broken) is from terminal a' to spring E, to break wheel D, to contact spring p, to anvil K, to contact spring o, p', to terminal a². If, under these circumstances, the train is released the box number only will be sent in, the circuit being interrupted by the notches in the break wheel passing under spring E. This call may be used and in fact generally is used by officer number one. If, however, the pointer wheel is previously turned so that the friction wheel of lever H rests in the second notch instead of the first notch, and the mechanism is then released the toothed sector d will engage with the teeth c and return the pointer wheel to its normal position, thereby giving one oscillation of lever H and one interruption of the circuit between p and K. The box number will then follow in the usual manner. This may be used and generally is used as the duty call of officer number two. In the same manner the pointer wheel can be turned one notch farther and a third duty call sent which may be used by officer number three. If, however, the pointer wheel shall be turned still farther so that the friction wheel rests in the fourth notch the arm L will come in contact with the spring e and force it into contact with the spring f. These contact springs e and f will be momentarily closed during the time that the first lug on the corner of arm L is in contact with the spring e and at the same moment the pin N will force the springs k and l together and the lever H will break the circuit between p and K. There will thus be a momentary circuit including part of the line a and part of the line b as follows: from battery Z to point 5, to point 4, to springs k, l, to springs e, f, to point 6, to terminal b³, to line b, to bell magnet W, armature relay X (this armature being retracted because the main line is interrupted between p and K) to the opposite terminal of battery Z. This circuit of course is only momentary, but it is maintained sufficiently to draw up the armature of bell magnet W which is thereupon latched and held in position to cause a continuous ringing of bell Q. The same break in the main line is recorded by the register magnet V and there follow two more breaks caused by the notches in the pointer wheel acting on lever H, and after that the box number. To describe this
- same signal otherwise it may be said that it consists of three breaks followed by the box number. The first of the three breaks being 70 accompanied by the ringing of the bell. In exactly the same way an ambulance call is sent, but it differs from the telephone call in that there are four instead of three breaks.
- 75 The next signal is the slow wagon call which is made by moving the pointer wheel a still greater distance. This call is the first of those which under my arrangement are sent to the stable. This call will be accompanied by the ringing of the bell W in the same manner as 80 the telephone call and the ambulance call, but it is different from the others as the register starts before the bell rings. The pointer wheel for this call is moved so far that the pin M is brought into contact with the spring 85 h so as to break its connection with the spring g. It may be noted in this connection that the lever O which starts the mechanism of the box always engages with the pin on spring m, but this has been of no effect in connection 90 with the previous signals because the circuit has still been maintained by connection between springs g and h, but as this latter connection is now broken for a slow wagon call by the pin M the separation of springs m and 95 n becomes effective and breaking line b releases armature of magnet U. The effect on the magnet U will be momentary, but the armature of the magnet will break the circuit of T, close the circuit of magnet S, and the 100 latter will close a short-circuit through itself and also close a circuit through the register magnet U' which will be a branch of the same circuit which passes through the magnet V. The result is that all of the breaks which affect 105 the main relay magnet X will be reproduced on the central station register magnet V and the stable register magnet U'. After the signal has been completed the clock work of the stable register which feeds the paper will interrupt the circuit of magnet S at S', and restore the parts to their normal condition. To trace this out in detail it must be remembered that the same operations are performed as in the case of a telephone or ambulance 110 call, the only difference being that the springs g and h are separated by setting the pointer wheel before the springs e and f, and the springs l and k are closed, as the former are closed by the return movement of arm L and 115 the latter by movement of the train. The pulling of the hook to start the mechanism also opens the contact between m and n in order to make effective the opening between g and h. The only object of this latter feature being to prevent any accidental sending of a slow wagon call by opening the springs g and h only, that is, an officer can turn the pointer wheel far enough to cause the pin to 120 separate the springs g and h, but that in itself 125 will not send a signal, and if he should change his mind for any reason he can turn the pointer back and no result will be secured. If, however, he should proceed to pull the re-

leasing hook he would open the springs *m* and *n* when the slow wagon call would go in. The main line *a* will have its circuit exactly as in the telephone and ambulance calls, 5 namely from the terminal *a'* to spring *p*, to anvil *K*, to springs *o*, *p'*, to terminal *a'*. It will be remembered that for the telephone and ambulance calls there is established a branch of the circuit just described, starting 10 from point 5, thence to point 4, to point 7, to springs *k*, *l*, to springs *e*, *f*, to point 6, to terminal *b*³ to line *b*, to bell magnet *W*, to the opposite terminal of battery *Z*. This branch followed a portion of the line *b* from the point 15 6, to the point 8, and thus did not include the battery *Y*. The remaining part of the circuit *b* which did include the battery *Y* extended (during telephone and ambulance calls) from battery *Y* to point 8, to point 6, to 20 the spring *m* and to spring *n*, either by direct contact or when direct contact is interrupted from the spring *m* to the spring *i*, spring *j*, springs *g*, *h* to the spring *n*, and thence by the terminal *b*² through the line to the stable 25 relay *U* to the opposite terminal of battery *Y*. This circuit, it will be observed, is always closed holding the armature of magnet *U* in its retracted position, but with the slow wagon signal this circuit is interrupted 30 at springs *g*, *h*, when the pin *M* comes in contact with the latter spring, and the effect of this break has been already described. It may be added, however, that the retraction of the armature of relay magnet *U* opens the 35 circuit of magnet *T* thereby releasing latching lever *T'*, which in turn releases the return lever *T*² which holds up the weight *W'* and when this weight is released it acts through an elbow lever to throw the rod *X'* 40 which acts through another elbow lever upon the latch *X*² of the stable door. The opening of the stable door closes the circuit of bell *V'* and allows the horses to go to the wagon. As has been before stated the dropping of relay 45 magnet *U* also closes the circuit of magnet *S* through local battery *S*². The attraction of the armature of magnet *S* closes a second local circuit from the battery *S*³ and the contact springs *S'* to the point 9 and the magnet 50 *S* to the opposite terminal of the battery. This circuit is maintained closed until the rotation of the feeding rolls of the register opens the contact between spring *S'* for a moment when the parts are restored to the condition shown 55 in the drawings. So long as the magnet *S* retains its armature a branch circuit from the battery *V*² is maintained through the register magnet *U'* at the stable so that the stable register and the central station register are both 60 controlled by the main relay magnet *X*. Just as in the telephone and ambulance calls so in the slow wagon call there follows a number of breaks produced by the notches in the pointer wheel and lastly the box number, all 65 of which are recorded both at the central station and at the stable.

The last call provided for is what is known as

the "fast wagon" call. For this call the pointer wheel is not turned, but the door of the box is left closed so as to bear against pin 70 *P'* and force the spring lever *P* inward so as to come into the path of cam *O'*. The turning of the key then depresses lever *P* by the agency of cam *O'* and releases the box mechanism by the arm *O*. The lever *P* remains 75 depressed while the calling lever or arm *O* and the cam *O'* are returned gradually to their normal positions by the running of the train, and while it is depressed it holds the circuit open between springs *i*, *j* and springs 80 *o*, *p'*, but holds the circuit closed between the springs *y* and *z*. The springs *o*, and *p'* when closed short-circuit the springs *w* and *v*, but when opened by lever *P* the short-circuit is broken and thus the separation of springs *w* 85 and *v* by means of cam *C*² will break the main circuit which will remain broken so long as cam *C*² is in contact with spring *v*. The circuit which is thus broken is from terminal *a'* to spring *E*, break wheel *D*, contact spring *p*, 90 anvil *K*, springs *w* and *v*, point 4, point 5 to terminal *a'*. This break in the main line causes a long dash to be recorded at the central station which is the distinguishing signal for a fast wagon call. Immediately upon 95 the occurrence of the break the spring *v* is forced into contact with spring *x*, and the latter is then forced away from the former by cam *C'*. The effect of this is to close a momentary branch circuit from the spring *v* to 100 the spring *x* to springs *y* and *z* (which are now in contact) to point 6, to line *b*, point 8, to bell magnet *W* and to the opposite terminal of main line battery *Z*. This rings the bell to indicate an emergency signal. The stable 105 relay is operated exactly as in the previous call except that the short-circuit around springs *m* and *n*, which was in the former case interrupted at the spring *g* and *h*, is now interrupted at the springs *i* and *j*. This will 110 be readily understood, but to make it clearer, the circuit may be traced as follows: from 115 terminal *b*² to spring *n*, thence (when springs *m* and *n* are separated) to spring *h* to spring *g*, to springs *j* and *i*, where the break in the line occurs, to spring *m* to point 6, to terminal *b*³, thence by line *b* to point 8 to battery 120 *Y*, to relay magnet *U*, line *b* to the starting point at terminal *b*². The retraction of the armature of magnet *U* when the circuit is 125 broken acts just as described above for a slow wagon call to set in operation the stable apparatus. It will thus be apparent in each instance where a wagon call is sent in that there is a momentary interruption of the circuit *b*, so as to bring into action the apparatus at the stable. It is observed that a portion of circuit *b* is also used at all of the calls except duty calls to energize the bell magnet *W* and thereby indicate that these are emergency calls requiring special attention. The same line *b* is moreover used as a telephone line over which communication can be had by 130 means of the telephones after the proper call

has been sent in. I have shown the telephones as placed in connection with the line by means of condensers in order that this function of the line may be utilized independently of its other functions.

I have not deemed it necessary to illustrate in detail the means by which the arm O and the cam O' are operated either by the releasing hook or the citizen's key as in this respect the device does not differ from that employed in the Gamewell signal boxes. It is sufficient to say that both the arm O and the cam O' are forced down by the hook or by the key then released and gradually return to their normal position.

It has been, I am aware, suggested that one or more individual signals may be received at some point outside the central station, but I believe that I am the first to provide means for transmitting a whole class of differentiated signals to a point outside of the central station without interfering with their distinguishing characteristics and to provide at the said point certain receiving apparatus responding to all signals of the class in common and other receiving apparatus responding differently to the responsive signals.

What I claim as new, and desire to secure by Letters Patent, is—

30 1. In a signal system the combination with one or more transmitters adapted to send signals having individual characteristics, of a central station, receiving apparatus thereat responding to the respective signals, means at each transmitter for distinguishing two or more signals as a class from the rest without changing their individual characteristics, a stable on the circuit and receiving apparatus thereat for the said two or more signals distinguished as a class, which apparatus responds differently to the respective signals in accordance with their individual characteristics.

2. In a signal system the combination with one or more transmitters adapted to send signals having individual characteristics, of a central station, receiving apparatus thereat responding to the respective signals, means at each transmitter for distinguishing two or more signals as a class from the rest without changing their individual characteristics, a stable on the circuit, receiving apparatus thereat for the said two or more signals distinguished as a class, which apparatus responds differently to the respective signals in accordance with their individual characteristics, and additional receiving apparatus at the stable responding to all of the said distinguished signals in common, which additional apparatus moreover controls releasing devices for the horses.

3. In a signal system the combination with one or more transmitters adapted to send signals of different kinds including a wagon call, and connected to the central station by two lines, the calls being sent upon one of the two lines and the distinguishing signal upon

the other, of a central station, apparatus therein for distinguishing and recording the different calls, a stable included in the circuit 70 of the line used for distinguishing signals and apparatus therein responding to the distinguishing signal for a wagon call.

4. In a signal system the combination with one or more transmitters, two lines connecting the said transmitters with a central station, a relay at the central station in one line and a relay at an outlying stable placed in the other line, with recording apparatus at the stable controlled by the relay in the first 80 line, and means at each transmitter for sending different signals on the first line, and a distinguishing impulse for one or more signals upon the other line.

5. In a signal system the combination with 85 one or more transmitters adapted to send signals of different kinds including a wagon call, of a central station and apparatus therein for distinguishing and recording the different calls, two circuits including the several transmitters and the central station, a stable and a loop extending thereto from the one of the said circuits which is used for the signal distinguishing the wagon call.

6. In a signal system the combination with 95 one or more transmitters adapted to send signals of different kinds including a wagon call, a distinguishing circuit for said call of a central station, apparatus therein consisting of a recording relay, a stable included in the rcc circuit used for the signal which distinguishes the wagon call, a magnet in the said circuit at the stable, and a branch from the local recording circuit at the central office extending to the stable and controlled by the said magnet.

7. In a signal system the combination of a central station, receiving apparatus therein, two circuits extending therefrom, one or more transmitters adapted to send upon one circuit signals of different kinds produced by definite combinations of breaks, a circuit closer with each transmitter having its opposite parts connected to the respective circuits whereby a distinguishing signal can be sent 110 over the other of the two said circuits, a circuit breaker in the latter circuit, a stable on said latter circuit and a relay therein controlled by the said circuit breaker.

8. The combination with a central station, 120 receiving apparatus therein for distinguishing and recording different kinds of signals, two circuits extending therefrom, a stable on one of said circuits, a relay therein and one or more transmitters on the said two circuits 125 for sending duty and emergency signals, each transmitter including a circuit breaker in one circuit for sending signals therein, a circuit closer for momentarily establishing a connection between the two circuits to indicate an emergency call, and a circuit breaker in the other circuit for distinguishing wagon calls and controlling the relay at the stable.

9. In a signal system the combination with

one or more transmitters adapted to send signals of different kinds including a wagon call, of a central station and apparatus there-in for receiving the respective calls, two cir-
5 cuits connecting the said transmitters and central station, one circuit being employed to send signals composed of several breaks, and the other circuit being momentarily em-
ployed to distinguish emergency calls and
10 wagon calls, a stable and receiving apparatus therein including horse-releasing devices and a loop connecting the stable with the said dis-
tinguishing circuit whereby the said receiv-
ing apparatus thereat may be set into opera-
15 tion by the momentary wagon-call signal on
said circuit.

10. The above described receiving appa-
ratus for a multiple signal system consisting of
a central station relay magnet, a recorder re-
20 sponding to all signals, and a bell responding
only to emergency calls, the said bell and re-
corder being located at the central station, with
a stable receiving relay responding to wagon
25 calls, a recorder responding differently to the
respective wagon calls, and horse-releasing
devices responding to all wagon calls.

11. The above described receiving appa-
ratus for a multiple signal system consisting of
a central station relay, recorder and bell
30 and a stable relay and recorder, the said sta-
ble relay responding to wagon calls and con-
trolling the circuit of the said stable recorder
which circuit is moreover controlled by the

central station relay, together with horse re-
leasing devices at the stable controlled by the 35
stable relay.

12. In a signal system the combination with
one or more transmitters and two lines con-
necting the same with the central station of a
circuit breaker at each station located in one 40
line for sending the different signals over the
said line, a battery in each line and circuit
controllers at each transmitter for sending
distinguishing signals over a part of one line
45 from the battery of the other line and for
sending a second distinguishing impulse for
a signal over the whole of one line, while the
signal itself is sent over the other line.

13. In a signal system with one or more
transmitters adapted to send signals of dif- 50
ferent kinds including telephone calls, the
combination of two lines connecting the said
transmitters with the central station, one of
said lines being a signaling line over which
the different signals are transmitted, the 55
other line being a telephone line, but pro-
vided with means for sending thereover a dis-
tinguishing impulse for emergency calls, and
a different distinguishing impulse for wagon
calls. 60

In testimony whereof I have hereto set my
hand this 24th day of October, 1893.

MICHAEL J. BURNS.
